TRUCK

Joseph T. Myers, 183 N. Prospect St., Kent, Ohio

Filed June 17, 1960, Ser. No. 61,017

Term of patent 14 years

(Cl. D14—3)

Fig. 1 is a side elevational view showing one side of a truck embodying my new design;

Fig. 2 is a front elevational view of the same;

Fig. 3 is a side elevational view of the same showing the side opposite Fig. 1; while

Fig. 4 is a rear elevational view of the same.

I claim:

The ornamental design for a truck, as shown.
